UNITED STATES PATENT OFFICE.

JULIUS BRENZINGER, OF MOUNT VERNON, NEW YORK, ASSIGNOR TO THE MAX. AMS MACHINE COMPANY, OF MOUNT VERNON, NEW YORK, A CORPORATION OF NEW YORK.

CAN-HEADING MACHINE.

No. 819,264.

Specification of Letters Patent.

Patented May 1, 1906.

Application filed October 19, 1905. Serial No. 283,367.

To all whom it may concern:

Be it known that I, JULIUS BRENZINGER, a citizen of the United States, residing at Mount Vernon, Westchester county, State of New York, have invented new and useful Improvements in Can-Heading Machines, of which the following is a specification.

This invention relates to a machine for forming the seam or joint between a can-body and its superposed head.

The machine is so constructed that the seaming means are advanced against the work in a simple, novel, and very efficient manner.

In the accompanying drawings, Figure 1 is a front elevation of my improved can-heading machine; Fig. 2, a right-hand side view thereof; Fig. 3, a left-hand side view of part of the same; Fig. 4, a horizontal section on line 4 4, Fig. 2; Fig. 5, a similar section on line 5 5, Fig. 2, with some of the parts omitted; Fig. 6, a side view of the can-feeding means; Fig. 7, a detail front view of the rack for vertically adjusting the can-supporting means; Fig. 8, a detail of the means for raising the cans; Fig. 9, a vertical section through the chuck and lower part of tubular shaft; Fig. 10, a detail plan, partly in section, of the machine-head; Fig. 11, a side view, partly in section thereof, with the chuck omitted; Fig. 11^a, a cross-section, partly broken away, on line 11^a 11^a, Fig. 11; and Fig. 12, a vertical section on line 12 12, Fig. 10.

The letter *a* indicates a normally stationary table or support upon which the cans to be closed are adapted to be placed. Table *a* is mounted on a vertically-adjustable support *b*, flanged to engage rails *A'* of the machine-frame *A*. Through a central opening of table *a* passes a vertical shaft *c*, stepped in bearings *b'* *b''* of support *b*. This shaft carries at a slight distance above table *a* a horizontal feed-disk *D*, that conveys the cans to be closed to the seaming means. The disk *D* is composed of a circular plate *d*, fast on shaft *c* and provided with a series of radial grooves *d'*. Within the latter are slidably fitted the shanks *d''* of a series of radially-adjustable forks or can-holders *d''*, which may be locked to plate *d* by clamp-screws *d''*. A curved peripheral guard *a'* of table *a* cooper-

ates with forks *d''* to insure a proper presentation of the cans to the seaming means hereinafter described.

Feed-disk *D* receives intermittent rotary motion in the following manner: To frame *A* is journaled a power-shaft *e*, which transmits motion by pulley *e'* and belt *e''* to a pulley *f'*. The latter constitutes part of the head *F* for operating the seaming-rollers and turns on a vertical stationary shaft *f*, mounted in frame *A*. To hub *f''* of pulley *f'* is secured a pinion *f'''*, that engages a gear-wheel *g'*, fast on a vertical shaft *g*. Shaft *g* is rotatably mounted in a bearing *A''* of frame *A* and carries at its upper end a pinion *g''*, engaging a gear-wheel *h'*, fast on a vertical shaft *h*. The latter is mounted in an upper bearing *A'''* of frame *A* and in a pair of lower bearings *b'''* *b''''* of support *b*. To shaft *h* is secured by groove-and-feather connection a gear-wheel *h''*, engaging a gear-wheel *i* of like diameter and pivoted to support *b*. To wheel *i* is fulcrumed at *i* one end of a link *i''*, the other end of which is pivoted at *i'''* to a lever *i''''*, loosely mounted on shaft *c*. To the free end of lever *i''''* is pivoted a spring-influenced pawl *i'''*, adapted to engage a ratchet-wheel *c'*, fast on shaft *c*. The number of teeth of ratchet-wheel *c'* is equal to the number of forks *d''*. It will thus be seen that at each complete rotation of shaft *h* wheel *i* will also make a complete rotation to advance ratchet-wheel *c'* for the length of one tooth. This partial rotation of ratchet-wheel *c'* will rotate forks *d''* for a space equal to the distance between the centers of two adjoining forks. In this way a new can will be presented to the seaming means, hereinafter described, at each complete rotation of shaft *h*.

After a can has arrived below the seaming means it is raised into engagement with the same in the following manner: Table *a* is provided with a circular opening *a''*, the center of which is vertically below the center of the seaming means. Opening *a''* is adapted to inclose an alined vertically-movable platform or plunger *j*, the surface of which is normally flush with the surface of table *a*, so that the cans may easily slide from table *a* upon platform *j*, and vice versa.

Platform *j* may be reciprocated so as to

bring the cans into or out of operative engagement with the seaming means in the following manner: To hub of wheel h^2 is connected a bevel-wheel h^3 , that engages a bevel-wheel k' of like diameter. Wheel k' is fast on a horizontal shaft k , turning in bearings b^5 b^6 of support b . Shaft k is provided with a cam k^2 , which is engaged by a roller l' of a lever composed of two parallel arms $l l$, that turn, 5 on a fulcrum b^7 of support b , Fig. 8. Arms $l l$ are connected by a transverse rod l^2 , upon which the roller l' is rotatably mounted. The free ends of arms l are connected by links l^3 to a collar j' , loosely mounted upon a 10 rod j^2 , that carries platform j . Upon collar j' are supported a pair of cushions j^3 , that bear against a collar j^4 , fast on rod j^2 . It will be seen that if the larger section of cam k^2 engages roller l' platform j will be raised, 15 while when roller l' is engaged by the reduced section of cam k^2 the platform will be lowered.

In order to positively lock feed-disk D while the seaming operation takes place—i. e., while pawl i^5 recedes from one tooth to 20 engage the succeeding tooth of ratchet-wheel c' —shaft k is provided with a second cam k^3 , which is engaged by a roller m' of a lever m , pivoted to support b at m^2 . The free forked end of lever m embraces a bolt n beneath a 25 collar n' , fast on said bolt. The latter is vertically slidable in bearings b^8 b^9 of support b and is normally retracted by a spring n^2 . The bolt n engages when raised one of a series of perforations d^5 of plate d , so that while 30 this engagement takes place feed-disk D is locked against rotation.

In order to instantaneously arrest the feed-disk and prevent its rotation by momentum after pawl i^5 has completed its forward 35 stroke, a brake c^2 , embracing shaft c , may be provided.

The seaming means hereinabove referred to consist of two pair of seaming-rollers, the rollers of each pair being placed diametrically 40 opposite each other. Means are provided for so actuating the rollers that while the first pair is advanced to operatively engage the can-body the second pair is retracted, and vice versa. The first pair of rollers is profiled 45 to form a lap-joint between can-body and can-head, while the second pair is profiled to impress said joint into a flat air-tight seam, a usual. The means for operating each pair of rollers are identical and are as follows: 50 The seaming-rollers o turn on upright axles o' of radially-movable slides O , adapted to rotate with head F around the can-body. The slides O are actuated by a stationary worm f^4 of shaft f and around which the 55 head F turns. This worm is engaged by worm-wheels p , there being one worm-wheel for each slide O . Each worm-wheel p is fast on a horizontal axle p' , rotatable in bearings f^5 of head F . To accommodate worm-wheels

p , the hub f^2 is slotted, as at f^6 . Each worm-wheel p is provided at each side with a fixed cam p^2 , such cams being engaged by a pair of rollers r' , pivoted to the forked end r^2 of a lever r . Each lever r is pivoted at r^3 to a support r^4 , secured to the bottom plate f^7 of head F . Lever r is provided with a downwardly-extending tailpiece r^5 , which is received by a corresponding perforation o^3 of an upper section o^4 of slide O . The slides O are guided in radial grooves f^8 of a downward extension f^9 of head F . In order to adapt the machine to cans of different diameters, each slide O has a lower section o^5 , radially movable with relation to the upper section o^4 . Section o^4 is provided with a radial guide-way o^6 , within which section o^5 is slidable. An adjusting-screw o^7 , turning in bearings o^8 of section o^4 , is received by an opening between parts o^4 o^5 and engages a thread cut into part o^5 , while it can rotate freely in the upper part of the opening formed in part o^4 . Thus by manipulating screw o^7 the lower part o^5 , which carries the seaming-roller o , may be moved radially inward or outward, so as to adapt the machine to can-bodies of different sizes. After the section o^5 has been properly adjusted it is locked in position by clamp-screws o^9 . To insure a ready rotation of rollers o , ball-bearings o^{10} may be interposed between the upper surface of such rollers and the section o^5 .

It will be readily understood that the rotation of head F and the corresponding revolution of worm-wheels p around fixed worm f^4 will result in a slow axial rotation of such wheels owing to their engagement with the worm. Wheels p will thus rotate cams p^2 , and when the enlarged sections of such cams engage rollers r' levers r will be tilted to force the slides O inward and bring the seaming-rollers o into operative contact with the can-head, so as to form the seam. The cams p^2 of the two pairs of seaming-rollers o are so set that while one pair is advanced the other pair is retracted, as will be readily understood. To the lower end of fixed shaft f is secured a fixed chuck s , which is adapted to enter a central depression T^2 of can-head T' , so as to hold the can-body T and cover T' in proper position while the seaming operation is performed, Fig. 9.

In order to insure a ready and positive disengagement of the cans from the chuck after the former have been closed, shaft f is made tubular and communicates at its upper end with a pipe u , which may be connected to a tank or other suitable means (not shown) for containing a pressure medium, such as compressed air. Pipe u is provided with a cock u' , which is operated by a spring-influenced lever u^2 , carrying a roller u^3 . This roller is adapted to engage a cam h^4 , connected to gear-wheel h' . When roller u^3 engages the

raised section of cam h^4 , valve u' is opened, while when the roller clears such section the valve will be closed by the action of a spring u^4 . The parts are so assembled that valve u' is opened upon the completion of the seaming operation and is closed before the next can-cover engages chuck s . The support b is vertically adjustable, as already stated, to adapt the machine to cans of different heights. For this purpose there is secured to frame A a rack v , which is engaged by a pinion v' , fast on a shaft v^2 , having hand-wheel v^3 and free to rotate in a bracket b^{10} of support b . The latter may be locked in position after it has been set by tightening a pair of clamp-screws v^4 , passing through slots A^4 of frame A and tapped into support b .

The machine operates as follows: Head F , together with shafts h and k , are continuously rotated by the means described. The can-body T , with superposed head T' , is placed upon table a between the shanks of one of the forks d^8 . By the intermittent rotation of fork d^3 the can-body will be carried against guard a' , which serves to center it within the fork. When the can has thus been pushed by its fork upon platform j , the latter will be raised to bring head T' into engagement with chuck s . The first and second pair of seaming-rollers, which revolve with the head F around the can, are now successively advanced to first form a lap-joint between the parts T and T' and to then flatten said joint. After the seaming operation has been completed platform j is lowered and the pressure medium is turned into tubular shaft f to forcibly disengage the can from the chuck. The can will now be pushed by one of the forks from platform j upon ta-

ble a and along the latter until it is thrown off the table by a suitable deflector a^3 , with which the table is provided.

What I claim is—

1. A can-heading machine provided with a fixed worm, a head rotatable around the same, slides radially movable along the head, seaming-rollers pivoted to the slides, and means actuated by the worm for operating the slides, substantially as specified. 50

2. A can-heading machine provided with a fixed worm, a head rotatable around the same, slides radially movable along the head, seaming-rollers pivoted to the slides, worm-wheels engaging the worm, and means actuated by the worm-wheels for operating the slides, substantially as specified. 55

3. A can-heading machine provided with a fixed worm, a head rotatable around the same, slides radially movable along the head, 60 seaming-rollers pivoted to the slides, worm-wheels engaging the worm, levers engaging the slides, and means actuated by the worm-wheels for oscillating the levers, substantially as specified. 65

4. A can-heading machine provided with a fixed worm, a head rotatable around the same, worm-wheels pivoted to the head and engaging the worm, cams rotated by the worm-wheels, levers operatively engaged 70 by the cams, slides engaged by the levers, and seaming-rollers pivoted to the slides, substantially as specified.

Signed by me at New York city, (Manhattan,) New York, this 18th day of October, 75 1905.

JULIUS BRENZINGER.
